UNITED STATES PATENT OFFICE.

GEORGE B. ARGO, OF PERLEE, IOWA.

CORK-EXTRACTOR.

No. 926,839.

Specification of Letters Patent.

Patented July 6, 1909.

Application filed February 2, 1909. Serial No. 475,825.

To all whom it may concern:

Be it known that I, GEORGE B. ARGO, a citizen of the United States, residing at Perlee, in the county of Jefferson and State of Iowa, have invented certain new and useful Improvements in Cork-Extractors; and I do hereby declare the following to be a full, clear, and exact description of the invention, such as will enable others skilled in the art to 10 which it appertains to make and use the same.

My invention relates to new and useful improvements in cork extractors and is adapted more particularly to be used for removing corks from bottles, etc., and my object is to provide a body, which may be introduced into or extended through the cork.

A further object is to provide means for extending prongs outwardly from the body 20 and in position to engage the cork and a still further object is to provide a shield for the lower end of the body when the extractor is not in use, said shield being arranged to form a handle for the extractor when in use.

Other objects and advantages will be hereinafter referred to and more particularly pointed out in the claims.

In the accompanying drawings forming part of this application, Figure 1 is a perspective view of the extractor when the same is not in use. Fig. 2 is an elevation thereof, showing the position of the parts when applied to use. Fig. 3 is a vertical central sectional view as seen on line 3—3, Fig. 2, and, 35 Fig. 4 is a similar view showing the parts of the device when not in use.

Referring to the drawings in which similar reference numerals designate corresponding parts throughout the several views, 1 indicates the body of my improved extractor, the lower end 2 of which is preferably pointed, while the upper end thereof is provided with a loop 3.

The body 1 is preferably oblong and provided adjacent its pointed end with a slot 4, which slot extends laterally through the body, said body being also provided with a longitudinal opening 5, the lower end of which communicates with the slot 4, while 50 the upper end thereof communicates with the opening 6 in the loop 3.

Extending through the opening 5 is a rod 7, the upper end of which is provided with a head 8, while the lower end thereof is provided 55 with a pair of curved prongs 9, said prongs being pivoted to the rod and adapted

to rest within the slot 4 when the rod is in its elevated position, or as shown in Fig. 4 and project outwardly from the edges of the slot when the rod 7 is in its lowered position or 60 when the rod is in the position shown in Fig. 3, the lower end wall 10 of the slot 4 being substantially V-shaped and curved to conform to the curvature of the prongs, thereby providing means for positively directing the prongs outwardly as the rod 7 is lowered.

When the extractor is not in use and the prongs 9 are housed in the slot 4, a tubular shield 11 is introduced over the pointed end 70 of the body 1, thereby obviating the possibility of injury from the pointed end of the body and at the same time holding the prongs within the slot, the closed end of the shield being also tapered, but having its 75 point more or less blunt. The shield 11 is also adapted to be used as a handle while extracting the cork, the pointed end thereof being introduced into the opening 6 and above the head 8 and by forcing the shield 80 through the opening until it is extended at equal distances on opposite sides of the loop, the rod 7 will be lowered its full extent and the prongs 9 extended to the position shown in Figs. 2 and 3, when the shield 11 may be 85 grasped and the cork extracted. The head 8 is preferably curved to conform to the curvature of the opening 6 and to prevent the head from mutilating the shield 11, a cavity 90 12 is formed in the opening 6, in which the head 8 is adapted to be seated when in its lowered position. It will be also noted that the head 8 of the stem 7 has primarily for its object to effect, in connection with the member 11, the locking of said stem, with its 95 prongs, in depressed or lowered position, as against the action of the object engaged by said prongs retracting said prongs or barbs from their engaging position.

This form of extractor may be very 100 cheaply constructed and at the same time rendered strong and durable and it will likewise be seen that the same may be quickly applied when it is desired to extract the cork. It will further be seen that the extractor when not in use will occupy a minimum amount of space and by employing the shield as a handle, sufficient gripping surface will be provided to quickly extract the cork.

What I claim is:

1. A device of the character described, comprising a body having an axial or longi-

tudinal opening therethrough terminating at its upper end in a recess of greater width than said opening, said body having a transverse opening at its upper end communicating with said recess, said body also having removed a short distance from its lower end a slot opening laterally therethrough, a stem arranged in said longitudinal opening and equipped at its lower end with pivoted 5 prongs arranged in said laterally opening slot, said stem having at its upper end a head adapted to be received by said recess and means insertible through the opening in the upper end of said body and adapted to engage 10 said head for its retention in said recess.

2. A device of the character described, comprising a body having an axial or longitudinal opening therethrough terminating at its upper end in a recess of greater width than 15 said opening, said body also having a transverse opening through it communicating

with said recess, said body also having a slot opening laterally therethrough a short distance from its lower end, a stem received by said longitudinal opening and provided at 25 its lower end with pivoted prongs arranged in said laterally opening slot, said stem also having a head at its upper end of arcuate outline adapted to be received by said recess, and a shield for the pointed end of the device 30 adapted to be received by the transverse opening in the upper end of said body and to engage the upper concaved surface of said head.

In testimony whereof I have signed my name to this specification in the presence of two subscribing witnesses.

GEORGE B. ARGO.
